UNITED STATES PATENT OFFICE.

ERNEST HYMAN, OF AUBURN, MAINE.

DESIGN FOR A HAND-BAG.

46,025.

Specification for Design.

Patented June 30, 1914.

Application filed March 18, 1914. Serial No. 825,701. Term of patent 7 years.

To all whom it may concern:

Be it known that I, ERNEST HYMAN, a citizen of the United States, residing at Auburn, Maine, have invented a new, original, and ornamental Design for Hand-Bags, of which the following is a specification, reference being had to the accompanying drawing, forming part thereof.

The figure is a plan view of a handbag, showing my new design.

I claim—

The ornamental design for a handbag, as shown.

ERNEST HYMAN.

Witnesses:

HARRY MANSER,
CORNELIA PULSIFER.
